VALVE GUIDE

Fredrick A. Lower, Wichita Falls, Tex.

Application August 18, 1932, Serial No. 629,315

1 Claim. (Cl. 123—188)

This invention relates to valve guides and it has particular reference to a replaceable guide for use in conjunction with poppet valves of internal combustion engines, particularly of the 5 heavy duty type.

The principal object of the invention is to provide in a valve guide of the character specified, a device which is readily replaceable and in which a thorough lubrication of all moving parts is pos- 10 sible.

Another object of the invention is the provision of means whereby the valve is held in alignment at all times.

Another object of the invention is the provision 15 of means whereby spring surging is eliminated.

Still another object of the invention is to pro- 20 vide a guide which is simple, inexpensive, and thoroughly dependable in use.

With the foregoing objects as paramount the 25 invention has particular reference to its salient features of construction and arrangement of parts, which will become manifest as the description proceeds, taken in connection with the accompanying drawing, wherein.

The figure illustrates the invention in vertical 30 section, showing the same attached to a cylinder head.

Continuing more in detail with the drawing, 1 designates the cylinder head of an internal com- 35 bustion engine, on which a rocker arm 2 is actuated by a conventional cam mechanism, not shown. A valve chamber housing 3 is rigidly attached to the cylinder head 1 as shown. The housing 3 is provided with removable plates 4 to aid in gaining access to the valve 5.

The valve guide proper is comprised of an upper guide 6 and a lower guide 7. The guide 6 is provided with threads at *a*, and is formed with a hexagon outer portion to provide for the application of a wrench. The guide 6 is provided

with an opening *b*, through which oil may be introduced, and lower portion 7 is filled with oil to keep all moving parts thoroughly lubricated.

The lower end of the stem of the valve 5 is threaded into the guide 7, which conformably receives the lower or skirt portion of the guide 6.

It can readily be seen that the guides 6 and 7 provide a mechanism which is readily adjustable and replaceable, simple in construction, and which embody other novel features, such as accessibility for lubrication, and complete guidance for the valve spring 8.

Manifestly, the construction shown is capable of considerable modification and such modification as is considered within the scope and meaning of the appended claim is also considered within the spirit and intent of the invention.

What is claimed is:

The combination with a valve chamber and a valve for reciprocation therein, having a stem 20 projecting beyond the said valve chamber, of a valve guide detachably fitted to the valve chamber and comprising a portion therein snugly receiving the valve stem, and a cylindrical skirt portion exterior thereto having an opening in its side, a guide carried by the valve and adjustable on the projecting portion of the stem and telescoping the cylindrical skirt portion of the first mentioned guide and cooperating therewith to provide a housing and an oil container, said 25 cylindrical skirt portion projecting into the adjustable guide portion for the major portion of its length, thereby facilitating the lubrication of the guide portion on the cylindrical skirt portion by contacting with the oil in said container upon 30 reciprocation of the valve, and a helical spring on the valve stem within the said housing and protected thereby and lubricated by the oil 35 therein.
